UNITED STATES PATENT OFFICE.

BERNARD RANSOME, OF DIABLO, CALIFORNIA.

PAVEMENT CONSTRUCTION.

Application filed February 26, 1925. Serial No. 11,655.

To all whom it may concern:

Be it known that I, BERNARD RANSOME, a citizen of the United States, residing at Diablo, county of Contra Costa, and State 5 of California, have invented new and useful Improvements in Pavement Construction, of which the following is a specification.

This invention relates to a paving structure and especially to a form of asphalt surfaced plank or timber by which track-crossings, roadways, floors, etc., which are subject to heavy traffic may be paved or covered.

15 The object of the present invention is to generally improve and simplify the construction and wearing qualities of pavements of the character referred to; to provide a paving material, comprising planks, timbers or the like, adapted to be placed side by side crosswise of a road or surface to be paved and each plank surfaced with a semi-resilient material such as asphalt or the like to form a wearing surface for the 20 planks; to provide an expanded metal strip for each plank to secure the surfacing material and to prevent creeping thereof when the pavement is completed, and further to provide a plank-supported pavement which 25 may be manufactured and entirely completed, except for the laying thereof, in a conveniently located centralized plant so that the material may be retained in stock 30 for immediate shipment and laying when required.

One form which my invention may assume is exemplified in the following description and illustrated in the accompanying drawings, in which—

40 Fig. 1 is a cross-section of a track-crossing showing the paving material laid and in position.

Fig. 2 is an enlarged cross-section of one of the paving planks.

45 Fig. 3 is a partial plan thereof.

Referring to the drawings in detail, and particularly to Figs. 1 and 2, A indicates a plank or timber formed of wood or any other suitable material. Forming a covering for the upper surface of the plank and extending from end to end thereof is a channel-shaped section of thin sheet metal. The flanges of the channel overlap the sides 50 of the timber and may be nailed or otherwise anchored thereto as indicated at 2. The channel thus secured on top of the timber 55

is provided for the reception of a surfacing material, such as an asphalt or bituminous mixture as indicated at 3, and for the purpose of securing the surfacing material a 60 key or bond is formed between the material and the metal by expanding or roughing the bottom surface thereof as shown at 4; that is, the bottom section of the channel is expanded or roughened in a manner similar 65 to plaster iron lath, such as used in building and partition construction, and as such forms an ideal key or bond between the surfacing material and the timber. The metal proper is not only secured to the plank 70 or timber by means of nails 2, but the expanded bottom section may also be secured by staggered nails such as indicated at 5.

The planks or timbers are treated if desired in the factory, for instance, by creosoting them or otherwise, and the metal channels are then applied to their upper surfaces and secured by means of the nails indicated at 2 and 5. The surfacing material, whether asphalt or otherwise, is then 80 filled in the channels and the surface thereof is raised to the point indicated at 6 in Fig. 2. The planks or timbers thus prepared are ready for use and may be shipped directly to their destination as required. They are 85 there laid side by side as shown in Fig. 1 and longitudinally V-shaped grooves are thus formed between them as indicated at 7. These grooves are filled with a liquid grouting of asphalt or bituminous material and 90 a finished, smooth, continuous surface is thus formed, and further more completes the operation of placing and laying the pavement. Where the pavement is used in connection with rail-crossings such as shown in 95 Fig. 1, heavy timbers are employed, but where the pavement is used on an ordinary roadway or for the floor of a wharf or factory, it is possible to use lighter planks or timber. The timber merely forms a foundation for the wearing surface and as such should be in proportion to the load or traffic handled.

By bonding or keying the surfacing material to each individual plank or timber as 105 here illustrated, it can readily be seen that creeping of the surfacing material is practically prevented, and it can furthermore be seen that a fairly thin layer may be employed as it is securely held in position by 110 the expanded bottom sections 4 and the channel edges 4a. Experience shows that

a thin coating or cover of asphalt or like material has less tendency to creep than a heavy layer, and as the covering or layer is in this instance bonded with relation to each individual plank, it is possible to form a covering as thin as desired; thus obtaining a smooth and permanent covering and wearing surface. It can furthermore be seen that a pavement of this character can be quickly laid as each plank in reality forms a complete section of the pavement; that is, the pavement is substantially completed at the factory and it is therefore only necessary to prepare the road bed and in place 15 the planks side by side when laying the same, and finally, to pour in the grouting material between the adjoining sections as indicated at 7. The work of laying the pavement is thus rapid and as the bond 20 formed between the surfacing material and the planking is exceedingly efficient, long life and durability can be assured.

While timbers or planks have here been referred to, I wish it understood that other materials, such as concrete, might be employed. It should also be noted that the asphalt or bituminous mixture might be substituted with rubber or any other semi-resilient material suitable for the purpose, 25 and further that various changes in form and proportion may be resorted to within the scope of the appended claims.

Having thus described my invention, what I claim and desire to secure by Letters Patent is—

1. In a pavement structure, a plank adapted to be laid crosswise of the pavement, a channel shaped section of sheet metal secured to the upper surface of the plank and 20 extending longitudinally from end to end thereof, a filler of semi-resilient surfacing material in the channel section and secured thereby, and a key member in the bottom of the channel to form a bond between the 45 channel and the filler.

2. In a pavement structure of the character described, a plank adapted to be laid crosswise of the pavement, a channel shaped section of sheet metal secured to the upper 25 surface of the plank and extending longitudinally from end to end thereof, the side portions of said channel member having downwardly turned flanges adapted to embrace the sides of the plank, and a filler of semi-resilient surfacing material in the channel section and secured thereby, said sheet metal channel having an expanded bottom section to form a key and bond between the 50 filler and the channel.

60 3. In a pavement structure a plank adapt-

ed to be laid crosswise of the pavement, an expanded sheet metal section secured to the upper surface of the plank and extending longitudinally from end to end thereof, a 65 filler of asphalt forming a covering for the expanded metal section and plank and keyed to the plank by the expanded metal section, and an upwardly projecting metal edge on each side of the plank extending from end to end thereof.

4. A pavement structure comprising a series of planks laid side by side, a channel-shaped section of sheet metal secured to the upper surface of each plank and extending from end to end thereof, and a filler of semi-resilient surfacing material in each channel 75 section, said sheet-iron channels having an expanded bottom section to form a key and bond between the filler and the planks.

5. A pavement structure comprising a series of planks laid side by side, a channel-shaped section of sheet metal secured to the upper surface of each plank and extending from end to end thereof, a filler of semi-resilient surfacing material in each channel 80 section, said filler extending above the upper edges of the channels and the side edges of the filler being shaped to form inclined faces so as to form a substantially V-shaped groove between each channel section, and a grouting material forming a 85 filler for each V-shaped groove to provide a continuous smooth surface.

6. A pavement structure comprising a series of planks laid side by side, a channel-shaped section of sheet metal secured to the upper surface of each plank and extending from end to end thereof, a filler of semi-resilient surfacing material in each channel 90 section, said filler extending above the upper edges of the channels and the side edges of the filler being shaped to form inclined faces so as to form a substantially V-shaped groove between each channel section, a grouting material forming a filler for each V-shaped groove to provide a continuous smooth surface, and an expanded bottom section in each channel forming, together with the channel edges, a key and a bond to 95 secure the filler and to prevent creeping thereof.

7. A paving material comprising a plank, a channel-shaped section of sheet metal secured to the upper surface of the plank and extending from end to end thereof, an expanded bottom section in the channel, and a semi-resilient filling material in the channel and keyed to the plank by the expanded bottom section of the channel.

BERNARD RANSOME.
